UNITED STATES PATENT OFFICE.

CHARLES L. EMENS, OF HOLTON, MICHIGAN.

BRICK-MACHINE.

SPECIFICATION forming part of Letters Patent No. 360,569, dated April 5, 1887.

Application filed September 27, 1886. Serial No. 214,649. (No model.)

To all whom it may concern:

Be it known that I, CHARLES L. EMENS, a citizen of the United States, residing at Holton, in the county of Muskegon and State of Michigan, have invented certain new and useful Improvements in Brick-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to that class of brick-machines wherein the clay is fed forward to the molds by means of a feed-screw, the object of my improvement being to avoid the end-thrust which is so characteristic of screw brick-machines, or, in other words, to provide mechanism by means of which the energy generated by the backward thrust of the screw-shaft, which is commonly expended or wasted upon a casting or other device for keeping the shaft in place, may be made to do actual work, thereby doubling the capacity of the machine with but a slight increase of driving-power; and the invention consists, essentially, in the combination, with the right and left hand feed-screw, of a mixing or tempering shaft; and, further, it comprises certain details in the construction, combination, and arrangement of the various parts, substantially as will be hereinafter described and claimed.

In the annexed drawings, illustrating my invention, Figure 1 is a vertical section of my improved brick-machine. Fig. 2 is a top plan view of the same, in partial section, on the line 11 of Fig. 1. Fig. 3 is a view of one of the covers for the outer ends of the compartments.

Like letters of reference denote like parts in all the figures.

A and A' represent oppositely-located duplicate compartments of the horizontal chamber which contains the feed-screw, said compartments being separated by an intermediate casing or box, G, joined to the basal portions of the compartments and containing journal-boxes H H, in which the horizontal shaft D is journaled. Within the casing G is also contained a gear, F, or other actuating-wheel, secured upon the shaft D between the journal-bearings. The opposite end portions of the

shaft D extend throughout the compartments A and A' to near the outmost extremities thereof, and are furnished, respectively, with a series, E, of left-hand augers, located in compartment A, and a series, E', of right-hand augers, located in compartment A', said screw portions being usually made tapering, and the compartments surrounding them being likewise tapered to conform to the screws. The horizontal chamber is conveniently supported by any suitable frame-work, such as the base N and uprights M M.

It will be evident that when my improved right and left hand screw is used as a feeder in a brick-machine, the horizontal end-thrust of the shaft, caused by the revolution of the right-hand screw in the firmly-bedded clay, will be opposed and counteracted by the horizontal thrust of the shaft in the opposite direction, caused by the revolution of the left-hand screw in the clay, and vice versa. The opposite tendencies to movement in the shaft will therefore balance each other, and the shaft will not be subject or liable to an end-wise displacement from its normal position.

In brick-machines as ordinarily constructed the end-thrust of the screw-shaft is guarded against by means of a heavy casting, against which the shaft abuts, or by making the bearing which holds the end of the shaft of considerable thickness and great strength. Should the casting or bearing give way, obviously the machine will be useless until repaired; but with my improved machine no such accident is possible, and there is no wasting of energy against a casting, but the thrust of one portion of the shaft sustains the thrust of the other portion, and this mutual counteraction of the two forces holds the shaft in equilibrium, as well as doubling the capacity of the brick-machine, with but a slight increase in the amount of driving-power required.

Above or otherwise centrally adjacent to the horizontal chamber is placed a chamber, B, joined to the horizontal chamber and communicating with it, there being an intervening space between the wall of the casing G and the point where the compartments unite with the bottom of the vertical chamber. This chamber B contains a tempering or forcing screw, C, constructed in any desirable manner, and adapted to carry the clay down through the

chamber after it has been fed into the upper end, and supply it in proper quantities to the compartments A and A', to be fed forward by the screws to the brick-molds.

5. The brick-molds are located at the outer extremities of the compartments A and A', and are arranged as follows: The outer ends of these compartments are covered and closed by means of plates or covers I, (see Fig. 3,) secured 10 in place by any suitable means, such as bolts. For a certain distance around the center of each cover it is made intact; but the remaining portion of the cover is provided with holes or apertures *a*, of proper shape and size to 15 correspond with the ends of the dies J, in which the bricks are molded, said dies being of the ordinary parallelopiped form and being secured within the holes or apertures *a* or made integral with the covers. I preferably 20 provide each of the covers with two dies, which lie parallel to each other and in the same horizontal plane.

The clay which is fed forward by the screws will strike against the covers I I and be forced 25 into the dies J J, from the outer ends of which it will emerge in compact bars, which may be cut into the desired lengths for bricks by any convenient cut-off mechanism. As is well known by those versed in the art of making 30 bricks, the clay which is directly in advance of the ends of the feed-screws has a spiral structure, which has been imparted to it by the screws; hence if the dies were in line with the axis of the screws the clay out of which 35 the bricks are formed would not be solid and compact, but would consist of spiral or convoluted laminations, and the resulting bricks would be of an inferior quality. I therefore situate the dies at a certain distance from the 40 centers of the plates I I, leaving the central portions of said plates intact, so that the spirally-formed clay may strike against them and

so that the clay which enters the molds may be freed of the spiral structures and the bars of clay which emerge therefrom may be firm 45 and solid.

Having thus described my invention, what I claim as new, and desire to secure by Letters Patent, is—

1. The combination, with the horizontal 50 chamber and the right and left feed-screw therein, of a tempering-chamber communicating with the horizontal chamber and containing a tempering-shaft which feeds the clay to the right and left hand screws, substantially 55 as specified and shown.

2. The combination of the horizontal chamber having duplicate compartments and an intermediate casing, a right and left hand feed-screw journaled in the intermediate casing, 60 a tempering-chamber located centrally adjacent to the horizontal chamber and communicating with the compartments of the latter, and a tempering or forcing device in the tempering-chamber, substantially as described. 65

3. The combination of the horizontal chamber having duplicate compartments and a casing intermediate between said compartments, the feed-screw provided with right-hand augers in one compartment and left-hand 70 augers in the other compartment, journaled in the intermediate casing, and actuated by devices applied to that portion of the shaft within the said casing, and a tempering-chamber and its shaft arranged opposite the middle 75 casing, so as to deliver clay to the duplicate compartments, substantially as described.

In testimony whereof I affix my signature in presence of two witnesses.

CHARLES L. EMENS.
